UNITED STATES PATENT OFFICE.

FRANK DE LORME, OF CENTRAL SQUARE, NEW YORK.

SIGHT FOR FIRE-ARMS.

SPECIFICATION forming part of Letters Patent No. 269,023, dated December 12, 1882.
Application filed September 19, 1882. (No model.)

To all whom it may concern:

Be it known that I, FRANK DE LORME, of Central Square, in the county of Oswego, in the State of New York, have invented new and useful Improvements in Adjustable Gun-Sights, of which the following, taken in connection with the accompanying drawings, is a full, clear, and exact description.

This invention relates to improved means for adjusting the sight on the barrel of a gun; and it consists in the combination and arrangement of parts hereinafter fully explained, and specifically set forth in the claim.

Referring to the annexed drawings, Figures 1 and 2 are transverse sections, taken respectively in front of and centrally through the sight; and Fig. 3 is a longitudinal section taken in the center of the barrel of the gun.

Similar letters of reference indicate corresponding parts.

B represents a rifle-barrel, and S the sight, which may be of any desired style or shape, fixed to a base, A, which is fitted to slide in a transverse dovetail groove or way, a, in the top of the barrel. This groove has a semi-cylindrical recess, r, extending from the center in opposite direction part way the length of the groove. On one end of the aforesaid groove another similar but short semi-cylindrical recess forms a shoulder, b, for the purpose hereinafter explained. The sight-base A is provided on its under side with a screw-threaded channel, c, extending nearly the length thereof, that end of the channel c which is over the shoulder b in the way a being smooth.

d is the adjusting-screw, having its threaded portion or screw proper, e, larger in diameter than its manipulating stem or end portion, and fitted into the recess r of the way a. The threads of said screw correspond with those of the channel c of the sight-base. From the end of the screw e projects a circumferentially-reduced extension, which has a blank neck, n,

adjacent to the screw e, and is screw-threaded 45 from a point over the shoulder b to its extremity, as shown at f, and on this screw-threaded portion is fitted a jam-nut, h, which, by its abutting against the shoulder b, serves to bind the adjusting-screw so as to prevent it from 50 turning.

The described devices are applied to the barrel of the gun and operated in the following manner: The adjusting-screw being placed in the recess r, the base A of the sight is entered 55 into the groove a and pushed up to the screw e, and is then drawn farther into the groove by turning the adjusting-screw. The jam-nut h is then applied to the extension f of the adjusting-screw. To adjust the sight in its required position, the adjusting-screw is turned to move the sight into said position, and then, while holding the adjusting-screw with one hand, the clamping-nut h is turned with other hand until it becomes firmly set against the 60 shoulder b.

Having described my invention, what I claim as new, and desire to secure by Letters Patent, is—

The combination of the barrel having the 70 groove or way a; provided with the recess r and shoulder b, the sight-base A, fitted to slide in the way a, and provided with the screw-threaded channel c, the adjusting-screw d, having its threaded portion e fitted in the recess r, and provided with the threaded extension f and intermediate blank-neck, n, and the jam-nut h, all as shown and described.

In testimony whereof I have hereunto signed my name and affixed my seal, in the presence 80 of two attesting witnesses, at Syracuse, in the county of Onondaga, in the State of New York, this 11th day of September, 1882.

FRANK DE LORME. [L. S.]
